UNITED STATES PATENT OFFICE.

THOMAS MEIKLE, OF LOUISVILLE, KENTUCKY.

CULTIVATOR.

SPECIFICATION forming part of Letters Patent No. 352,554, dated November 16, 1886.

Application filed August 5, 1886. Serial No. 210,074. (No model.)

To all whom it may concern:

Be it known that I, THOMAS MEIKLE, of Louisville, in the county of Jefferson and State of Kentucky, have invented new and useful Improvements in Cultivators; and I do hereby declare that the following is a full and accurate description of the same, having reference to the accompanying drawings, in which—

10 Figure 1 is a perspective view of my invention. Fig. 2 is a side elevation of my coupling detached from the side bar. Fig. 3 is a cross-section of the same, showing the clamp in action.

15 The object of my invention is to provide an efficient and cheap mode of adjusting the cultivator-shovels both as to elevation and angle, not subject to derangement by any lack of intelligence on the part of attendants; and 20 it relates to that class of adjustable hoes which are provided with clamping devices of some sort attached to the beam to seize and hold the shanks of the hoes.

I am aware that cultivator-hoes have been 25 made heretofore with cylindrical shanks, and that clamps have been placed upon the beams to receive and hold said shanks, and that such clamps have been made in considerable variety. Therefore I do not propose to broadly 30 claim herein that mode of securing and holding the hoe-shanks; but I am not aware that any one has heretofore constructed for a cultivator-hoe with a cylindrical shank a clamping-coupling pivoted to the beam or drag-bar with 35 the clamp in the line of draft, so that all side strains are avoided.

A is my drag bar or beam, preferably made from two flat bars of metal. At the front the beam is connected to the clevis or draft-frame 40 in some proper way, and there may be two or more of said beams, as desired. Ordinary or suitable handles are also provided for the management of the cultivator while in use.

45 At the rear end of the beam is my coupling B, preferably made of malleable iron, with a central web and marginal ribs for strength transversely. About midway its length it has a bolt-hole for the coupling or pivot bolt d, which passes through both parts of the 50 beam and through the plate B, between them.

At its forward end the plate B is provided with a transverse slot or notch, e, for the clamp-bolt f, whereby when the plate B has been adjusted as to angle it is clamped to the beam and fixed in position. At the rear end 55 of the plate B there is a vertical socket, g, to receive the cylindrical shank H of the cultivator-hoe I and allow it to be turned to set said hoe at any angle to the line of advance, or to slip up or down to set said hoe at any 60 desired vertical distance below the beam. The socket g is divided transversely by the notch k, in which I place the eye of the eyebolt L, so that the shank H passes through said eye. The screw-shank of said eyebolt 65 passes through the saddle M, which rests against the outside of the socket g and spans the notch k, and a nut, n, upon the outside of said saddle, when tightened up, serves to clamp the shank H fast in the socket g. 70

The saddle M may be made integral with the socket g; but I have preferred to make it separate therefrom.

By separating the beam in two parts longitudinally, and by placing the socket g in 75 the end of the coupling B directly in line with the beam and the shank H of the hoe, the draft-strains are transmitted in direct lines, and all torsional or side strains are avoided. This is a matter of importance, because the relief is 80 felt in every part, and the beam and coupling B may both be made with less weight than heretofore, and therefore more easily and cheaply.

Having described my invention, I claim— 85

1. In combination with the cultivator-beam A, the coupling B, provided at its front end with the slot or notch e, and at its rear end with the socket g, and clamp to hold the shank H in position as adjusted, substantially as set 90 forth.

2. The drag-bar A and the cultivator tooth and shank H, combined with the coupling-plate B, pivoted to said drag-bar on a horizontal axis, whereby the vertical angle of said tooth and shank may be adjusted, said clamping-plate having the socket g at one end and in line with the length of said plate, and the transverse notch k, and with the eyebolt L and saddle M, whereby said shank may be ad- 100

justed vertically and draft strains be transmitted through said coupling in the line of its length.

3. A cultivator having each of its drag bars or beams A constructed with two parallel metallic bars, combined with a coupling, B, adapted to enter between said bars and be secured thereto by pivot-bolt *d* and clamp-bolt

f, said coupling being provided with a socket, *g*, and a clamp to receive and hold the shank *h* of the cultivator-hoe in the direct line of draft, as and for the purpose set forth.

THOMAS MEIKLE.
